INSERT CORE FOR SLIDE SHUT-OFF DEVICE
James Woodburn, Jr., Wheaton, Ill., assignor to Amsted
Industries Incorporated, Chicago, Ill., a corporation of
New Jersey

Filed Aug. 24, 1960, Ser. No. 51,657
4 Claims. (Cl. 22—84)

This invention relates to the art of bottom casting in which molten metal or other fluid material is forced into a bottom gate of a mold, and the invention relates more particularly to novel means for cutting off flow of such material and to a method of producing such means.

According to prior art practices, the fluid material enters the gate through an aperture of a cut-off slide which is actuated to close the gate when the mold has been filled. According to such practices, the aperture has been bushed to accommodate reuse of the slide.

However, such practices have been limited to low melting point alloys such as white metal and other low melting point nonferrous metals which do not cause excessive erosion of the bushings during the pouring.

According to the invention, it has been discovered that conventional core sand bushings, although effective in such prior art practices, are not suitable for the casting of iron, steel, and similar high melting point ferrous and nonferrous metals which must be poured at temperatures in excess of 1500° F. and at velocities which cause excessive erosion of such prior art bushings.

Early efforts to solve this problem involved the substitution of a fired refractory material for prior art sand core bushings; however, such material proved to be costly and to require expensive molding or machining to suitable form.

According to the invention it has been discovered that a satisfactory composite bushing can be produced by forming a conventional core sand mix sleeve around the perimeter of a fired refractory liner in such manner that the sleeve and liner are bonded to each other to form a composite bushing which can be quickly and economically assembled by manual insertion into the top of an aperture in a cut-off slide.

The foregoing and other objects of this invention will become apparent from a consideration of the following specification and the accompanying drawings, wherein:

FIGURE 1 is a perspective view of casting apparatus embodying a preferred form of the novel composite bushing;

FIGURE 2 is a top plan view of the cut-off slide assembly shown in FIGURE 1;

FIGURE 3 is a fragmentary sectional view on line 3—3 of FIGURE 2;

FIGURE 4 is a fragmentary side elevational view of the structure shown in FIGURE 2;

FIGURE 5 is a sectional view on line 5—5 of FIGURE 4;

FIGURE 6 is a central vertical sectional view through a core box and composite bushing formed therein according to one manner of practicing the novel process; and

FIGURE 7 is a view corresponding to FIGURE 6 but showing another manner of practicing the novel process.

Describing the invention in detail, a mold assembly generally designated 2 (FIGURE 1) comprises a mold 4 which may be of a chill material, such as graphite or of any other desired ceramic material well known in the art, such as sand or shell. The assembly 2 also comprises a car 6 to which the mold 4 may be clamped by conventional clamps 7 or by force of gravity. The mold 4 and car 6, during a pouring operation, as hereinafter described, move together as a unit or assembly 2 and may be interconnected in any desired manner.

2

The car 6 comprises wheels 8 which roll on tracks 10 and also comprises a cut-off or gate closing device generally designated 12. The cut-off 12 is best seen in FIGURES 2—4 and includes a slide support 14 having an opening or hole 15 with a bushing 16 (FIGURE 3) formed as hereinafter described. The slide support 14 has a cut-out or slot 18 (FIGURE 2) partly defined by an inner edge 20 for a purpose hereinafter described.

A slide or plate 22 preferably of cast iron, copper or any other desired chill material is slidably mounted on the support 14 and comprises an opening or aperture 24 having a bushing 26 similar in form and composition to bushing 16, as hereinafter described. The slide 22 is supported within a channel 28 (FIGURE 4) of the support 14 and is seated along a surface thereof immediately below another channel 34 within which is positioned a loose insert 36 (FIGURES 2 and 3) which is complementary to and removably mounted in an opening 38 of a top plate or panel 40 of the car 6.

The support 14 is releasably interlocked with the panel 40 by means of ears 42 on the support having apertures within which are received lugs 46 on the underside of panel 40. The lugs 46 are slotted to receive wedge keys 48 which are driven to locking position shown in FIGURE 4 and which may be quickly removed by an impact against the small ends of the keys 48.

The insert 36 is provided with an opening or aperture 50 having a bushing 52 (FIGURE 3) similar in form and material to bushings 16 and 26, whereby when apertures 15, 24 and 50 are aligned, they define a continuous passage for the flow of molten metal into a gate 54 (FIGURE 3) of the mold 4.

The assembly 2 rolls along rails 10 (FIGURE 1) until the apertures 15, 24 and 50 are located in vertical alignment with the top of a pouring tube 58 (FIGURE 4), the lower end of which communicates with a source of fluid material (not shown) to be cast, such as a ladle of molten steel. Under these conditions, the wheels 8 are supported by rail segments 10a which are separable from rails 10 and are vertically movable.

The segments 10a are supported by a frame 60 which is in turn supported at its corners, as by conventional worm gear screw jacks 62. The jacks are mounted on foundation-supported beams 66 and raise or lower the frame 60, as desired. The car 6 is guided at each side thereof in aligned relationship with the top of tube 58 by foundation-mounted guide rails 71 (FIGURE 1) which snugly confine therebetween a pin 73 on panel 40 of car 6.

When the assembly 2 is aligned with the top of tube 58, the jacks 62 are actuated to lower the frame 60 until a tapered recess 74 in the bottom of the support 14 engages a complementary tapered portion 76 (FIGURE 4) of the upper end of tube 58. The frame continues to lower until the support 14 is clamped by force of gravity or by other means (not shown) against the tapered portion of tube 58 to afford a seal tight to liquid metal between the tube and the support 14, whereupon the molten steel in which the tube 14 is immersed is pressurized (as for example in the manner disclosed by U.S. Letters Patent No. 2,847,739 issued August 19, 1958 to E. Q. Sylvester) to flow the metal upwardly through apertures 15, 24 and 50 and gate 54 until the mold has been filled. Tilting of the car 6 during pouring is limited by lugs 75 (FIGURE 1) mounted on the top of brackets 114, hereinafter described.

After the mold has been filled the slide 22 is actuated, as hereinafter described, to cut-off flow of molten metal through the gate, whereupon pressure on the molten metal is released, the rail segments 10a are elevated to mating relationship with rails 10, and the assembly 2 is rolled along the rails away from tube 58, and another assembly

2 is rolled into position and poured as heretofore described.

The manner in which the cut-off 12 is actuated can best be seen in FIGURE 4, wherein it will be seen that when the assembly 2 is supported on top of the tube 58, a power device 78 mounted on a cover 80 of a chamber or tank 81 containing the molten steel is disposed between the slide 22 and an abutment 82 depending from the underside of car panel 40 so that actuation of the device 78, as by hydraulic or pneumatic pressure, to expand the device 78 axially thereof causes a cylinder member 84 of the device 78 to engage the abutment 82 and a ram or piston member 86 of the device 78 to engage the cut-off slide 22.

The device 78 has a limited stroke and at the end of said stroke, the slide 22 is at a position whereat its aperture 24 is beyond edge 20 of the support 14, whereupon molten metal in aperture 24 is dumped through slot 18 so that the bushing 26 need not be replaced for each pouring operation. Also release of pressure on the molten metal in the tank 81 dumps the metal in bushing 16 so that it need not be replaced for each pouring operation.

The device 78 is afforded a floating support so that, upon actuation thereof, the forces developed by the device 78 to actuate the cut-off 12 to closed position are self-contained within the assembly 2. This support comprises a bracket 88 mounted on top of the cover 80 as by welding at 90. The bracket comprises a V-shaped channel 92 (FIGURE 5) within which a complementary slide 94 is positioned. The cylinder member 84 is clamped into the slide 94 by clamp rollers 98 on levers 100 pivotally fulcrumed at 102 (FIGURE 5) to the slide 94 and actuated by a compression clamping spring 104.

Upon energization of device 78, as heretofore described, the slide 94 permits enough axial movement of the device 78 so that the forces developed thereby are self-contained within assembly 2 and substantially no reactive forces are transmitted to bracket 88 or cover 80.

Upon removal of cylinder 84 from the clamps 98, which can be accomplished by manually lifting the cylinder to compress spring 104, the spring 104 is held in position upon bosses 112 of levers 100 by a slight force provided by a tension spring 113 connected to the lower ends of lever 100.

It may be noted that the cover 80 may be clamped to the top of its container 81 by clamp means (not shown) mounted on foundation-supported brackets 114, and the rail segments 10a may be manually removed from and replaced upon the frame 60 to accommodate insertion and removal of the cover 80 and a ladle (not shown) of molten steel into which the tube 58 extends. The construction of the container 81, the ladle (not shown), the cover 80 and tube 58 is per se no part of the present invention and may be of the type disclosed in said U.S. Letters Patent, or if desired, may be of any other desired construction and arrangement, with the tube mounted on the cover or elsewhere in communication with the molten steel in the container 81.

It should be noted that bushings 16, 26 and 52 are flanged at their upper ends so that in their aligned position shown in FIGURE 7, the flange of bushing 16 engages slide 22, the flange of bushing 26 engages insert 36 and the flange of bushing 52 engages the mold 4 around its gate 54.

According to the invention, each bushing 16, 26, and 52 is of novel form and comprises a prefired refractory liner 118 bonded to a flanged sleeve 120, as shown for example in FIGURE 6, wherein a novel method of making such a bushing is disclosed. The liner 118 is formed of a hard fired material such as graphite containing clay refractories so that the liner 118 does not erode substantially during the pouring and shut-off steps of a cycle as heretofore described. Such material cannot be economically molded to the desired bushing form and, according to prior art practices, must be machined to

that shape from a segment of a refractory tube, which is also an expensive procedure.

According to the invention, the liner 118 is cut to desired length from a standard tube and is sleeved over a complementary boss or center arbor 119 of an annular member 122 having a metal ring 124 sleeved thereon to form a metal core box which can be preheated to a desired temperature. The ring 124 is recessed as at 126 to define a larger diameter portion of the opening in ring 124, within which opening the liner 118 is positioned.

A mixture of conventional shell mold zircon sand and 2% (by volume) phenolic liquid thermosetting resin is poured around the liner 118 and is struck off flush with the top of the ring 124. This mixture bonds with the liner 118, the contacting surface of which is of sufficiently irregular contour to afford a good bond. After the resin has set, the novel composite bushing 118-120 is removed from the core box 122, 124 by ejector pins 128 having release springs 129.

FIGURE 7 shows a modification of the novel process wherein the shell mold sand mixture heretofore described is blown into core box 122, 124 by a conventional blow head 130, the member 122 being provided with suitable vents 132 screened as at 134.

It will be understood that, if desired, the apparatus of FIGURE 7 can be utilized to form a sleeve 120 from a sodium silicate-CO₂ bonded sand by blowing into core box 122, 124 a mixture of silica sand and 5% (by volume) sodium silicate. In this practice, the core box 122, 124 is not heated and after the blow head 130 has been removed, a similar blow head is positioned on core box 122, 124 to blow CO₂ gas through the core box until the sleeve 120 has hardened.

Also, if desired, the sleeve 120 may be formed in the core box 122, 124 of FIGURE 7 by charging blow head 130 with a conventional mixture of, for example, 1½% (by volume) corn cereal, 2% (by volume) linseed oil, 3% (by volume) water, and the remainder conventional silica core sand. After the core box 122, 124 has been filled with this mixture by blow head 130, the latter is removed, and the core is ejected and baked in a conventional core oven until hard, as for example, at about 425° F. for about two hours.

After the composite bushing 118-120 has been formed as heretofore described, it is hand fitted into an assembly such as heretofore described in connection with FIGURES 2 and 3, and it will be understood that all bushings 16, 26 and 52 may be formed as composite bushings 118-120 and may be assembled in the foregoing manner.

Moreover, if desired, the composite bushing 118-120 may be formed in situ within its opening 15, 24, or 50 by eliminating member 124 and inserting member 122 in such opening and thereafter forming the bushing 118-120 by any of the foregoing methods.

I claim:

1. In a device for pouring molten high melting point metal into a mold through a bottom gate, the combination of a cut-off slide having an aperture registered with the gate, a bushing in said aperture comprising a sleeve with a flange recessed in the slide, a hollow cylindrical refractory liner in the sleeve, said sleeve being snugly fitted in the aperture and being formed of sand particles bonded to each other and to said liner by a binder said liner being formed of a refractory material more resistant to erosion by said molten metal than said sleeve, and means for actuating the slide to a position where it cuts off flow of said molten metal from said bottom gate when the mold has been filled therewith.

2. In a method of forming a bushing for a cut-off slide having an aperture through which molten high melting point metal flows into a mold gate, the steps of inserting a refractory liner into said aperture, and then filling the aperture around said liner with a mixture of

sand particles and fluid bonding material which, when set, bonds the particles to each other and to the liner and slide, to form a sleeve around the liner.

3. In a device for pouring molten high melting point metal into a mold through a bottom gate, the combination of a cut-off slide having an aperture registerable with the gate, a bushing in said aperture comprising a sleeve with a flange recessed in the slide, a cylindrically shaped refractory liner in the sleeve, said sleeve being snugly fitted in the aperture and being formed of sand particles bonded to each other and to said liner by a binder. 10

4. In a cut-off device for molds for high melting point metals, the combination of: a cut-off slide having an aperture therethrough; a bushing in said aperture com- 15

prising a sleeve with a flange recessed in said slide; a refractory liner in said sleeve; said sleeve being snugly fitted in the aperture and being formed of sand particles bonded to each other and to said liner by a binder; said liner being formed of a refractory material more resistant to erosion by said molten metal than said sleeve.
